(57) **CLAIM**

The ornamental design for a tire tread, as shown and described.

DESCRIPTION

FIG. 1 is a perspective view of a tire tread, showing my new design;

FIG. 2 is a front view thereof;

FIG. 3 is a side view thereof;

FIG. 4 is an opposite side view thereof;

FIG. 5 is an enlarged perspective view of a section of the tire tread defined by lines 5-5 in FIG. 1;

FIG. 6 is an enlarged front view of a section of the tire tread as defined by lines 6-6 in FIG. 2; and,

FIG. 7 is an enlarged side view of a section of the tire tread as defined by lines 7-7 in FIG. 3.

In the drawings, the broken lines depict environmental subject matter only and form no part of the claimed design. The dash and dash dot lines on either side of the tire tread section in FIGS. 5-7 is for the purpose of illustrating the boundary of the claimed design and form no part thereof.
